COLLAPSIBLE CONTAINER

Ralph Mancuso, Brooklyn, N. Y., assignor to National Card Mounting Company, Inc., New York, N. Y., a corporation of New York

Application November 26, 1937, Serial No. 176,450

5 Claims. (Cl. 229—23)

This invention relates to collapsible containers, of sheet material, such as cardboard or the like and has for its object to provide a device of the character specified, simple in construction, easily erected into receiving condition, and having unusual features of strength and rigidity.

To these ends and others which will appear later herein my improvements comprise features illustrated in the drawings accompanying this 10 specification, wherein

Figure 1 is a front perspective elevation of my improved container in erected condition.

Fig. 2 is an upright cross section on line 2—2 of Fig. 1, looking in the direction of the arrows 15 in Fig. 1.

Fig. 3 is a vertical cross section similar to that of Fig. 2, but showing the device in collapsed condition, ready for packing in quantity for shipment.

Fig. 4 is a plan view of one of the two members 20 of the device in flat form as cut from some suitable sheet material such as cardboard and

Fig. 5 is a similar plan view of the other member of the device.

Fig. 6 is a front perspective elevation of a modification of my improved container in erected condition.

Fig. 7 is a front perspective elevation of a further modification of said container.

Figs. 1, 4, 5, 6 and 7 are to a scale about one 30 third of the preferred size of the actual container and Figs. 2 and 3 are to a scale about one half actual size.

The general character of my container is of a known type, but has features of simplicity and 35 rigidity, and economy of construction which are believed to be novel in the art.

Referring first to Fig. 4, the main member of my device comprises a back wall 2 comprising an upstanding panel 3 adapted to bear printed or 40 pictured display matter referring to merchandise in the container.

Converging slightly downwardly from opposite sides of panel 3 are folding score lines 4, 5, terminating at the bottom, thereby forming opposite 45 wings 6, 7 which in their turn terminate in ears 8, 9 defined from wings 6, 7 by score lines 10, 11 parallel with score lines 4, 5, all respectively.

About half way between the top and bottom of wings 6, 7 is a transverse cut 12 extending from 50 score line 10 to score line 11 thereby dividing the main member into two portions A and B. Midway its length cut 12 may rise into a half circle 12a to provide a simple ornamental feature to the front of the container, see Fig. 1.

55 Referring now to Fig. 5, therein is shown the

second member of my improved container comprising a back wall divided into three panels 13, 14, 15 by score lines 16, 17, said score lines converging slightly toward the bottom of said back wall and spaced apart similarly to the lower portions of score lines 4, 5 of Fig. 4. Outer panels or wings 13, 15 terminate in ears 18, 19 defined from wings 13, 15 by score lines 20, 21 parallel with score lines 16, 17, all respectively. Score lines 20, 16 and 17, 21 are spaced apart equal distances 10 to score lines 10, 4 and 5, 11 of Fig. 4 whereby wings 6, 13 and 7, 15 are of equal width, all respectively.

Projecting downwardly from mid-panel 14 is bottom member 22, attached to said mid-wing 15 along horizontal score line 23 and separated therefrom by opposite cuts 24, 24a and from opposite wings 13, 15 by opposite cuts 25, 26, all respectively.

Bottom 22 is of approximately hexagonal shape 20 and is divided into approximately equal parts by transverse score line 27. That part above said score line terminates transversely in feet 28, 29 divided therefrom by score lines 30, 31 and that part below score line 27 terminates transversely 25 in feet 32, 33 divided therefrom by score lines 34, 35, all respectively. Bottom 22 terminates downwardly in front foot 36, divided therefrom by score line 37.

In assembling the two members of my improved 30 device, the blank of Fig. 4 is superposed upon the blank of Fig. 5, with ears 8, 9 in register with ears 18, 19 respectively, and ears 8 and 18, and ears 9 and 19 are secured together by some convenient means as an adhesive or preferably by 35 means of wire staples 38, 38.

Lower portion B of the main member is then drawn forward, and bottom 22 is folded forwardly along score line 23 and against itself along score line 27 and pushed up behind main member portion B, whereby front foot 36 is brought into contact with the lower part of portion B and secured thereto by wire staples 39, 39.

The device will then appear as in Fig. 3. In 45 opening out the device for the reception of merchandise, feet 28, 29, 32, 33 are bent downward at right angles to bottom 22, thereby providing substantial support for said bottom, Fig. 2. Panels 13, 14, 15 form a substantial support at the back for the short wall A and the upper portions 50 of wings 6, 7, thereby producing a novel and rigid construction.

To illustrate shapes other than hexagonal for the bottom member of my improved container, Fig. 6 shows a bottom 40 of irregular pentagonal 55

- outline without a transverse folding line as 27 in Fig. 5, but having feet 320, 330 on the forward edges. Also member BB has one central vertical folding line instead of two, as in Figs. 1 and 4.
- 5 When collapsed bottom 40 folds upwardly against wall AA.

Referring now to Fig. 7, therein is illustrated a multi-side bottom 220 giving the appearance of a curved front B2 to the container. In this modification bottom 220 has a cross folding line similar to that at 27 in Fig. 5 and a front foot 330 similar to foot 36 of said Fig. 5. In Fig. 7 ears 80, 90 are given an ornamental contour which may be in consonance with the character of the merchandise displayed.

There is thus provided a container of two members only, adaptable to various shapes, economical in material and easily assembled with accuracy.

I claim:

- 20 1. A collapsible container of sheet material including in combination a main member comprising a mid-panel, two opposite wings articulated thereto and two opposite ears articulated to said wings respectively, a transverse cut dividing said mid-panel and said wings into an upper portion and a lower portion, a second member comprising a back wall having a mid-panel, two opposite wings articulated thereto and two opposite ears articulated to said wings respectively,
- 25 30 a bottom member of polygonal form articulated at its upper edge to said mid-panel, opposite feet articulated to the opposite edges of the lower portion of said bottom member, means for attaching the opposite ears of the main and second member together respectively, said second member being located behind said main member and adapted to reinforce the upper portion of said main member, the lower portion of said main member being brought forward to admit the
- 35 40 45 bottom portion of the second member, the opposite feet of the bottom member being foldable downwardly for supporting said bottom member when the device is erected, the whole being foldable into collapsed condition by folding the bottom member upwardly against the main member mid-panel.

2. A collapsible container of sheet material including in combination, a main member comprising a mid-panel and two opposite wings articulated thereto, a transverse cut dividing said mid-panel and said wings into an upper portion and a lower portion, a second member comprising a back wall having a mid-panel and two opposite wings articulated thereto, a bottom member of polygonal form, articulated at its upper edge to said mid-panel, a transverse score line dividing said bottom member into approximately equal parts, a downwardly reaching foot articulated to the bottom edge of said bottom member, means for hingedly connecting the outer edges of the wings of the main member and the second member respectively, said second member being located behind said main member and adapted to reinforce the upper portion of said main member, the lower portion of said main member being brought forward to admit the bottom portion of the second member and means for securing the downwardly reaching foot of the bottom member to the lower portion of the mid-panel of the main member, the whole being foldable into collapsed condition by folding the bottom member upwardly against the main member mid-panel.

3. A collapsible container of sheet material including in combination, a main member com-

prising a mid-panel and two opposite wings articulated thereto, a transverse cut dividing said mid-panel and said wings into an upper portion and a lower portion, a second member comprising a back wall having a mid-panel and two opposite wings articulated thereto, a bottom member of polygonal form, articulated at its upper edge to said mid-panel, a transverse score line dividing said bottom member into two parts, a downwardly reaching foot articulated to the bottom edge of said bottom member, means for hingedly connecting the outer edges of the wings of the main member and the second member respectively, said second member being located behind said main member and adapted to reinforce the upper portion of said main member, the lower portion of said main member being brought forward to admit the bottom portion of the second member and means for securing the downwardly reaching foot of the bottom member to the lower portion of the mid-panel of the main member, the opposite feet of the bottom member being foldable downwardly for supporting said bottom member when the device is erected, the whole being foldable into collapsed condition by folding the bottom member upwardly along its transverse score line, against the main member mid-panel.

4. A collapsible container of sheet material including in combination, a main member comprising a mid-panel, two opposite wings articulated thereto and two opposite ears articulated to said wings respectively, a transverse cut dividing said mid-panel and said wings into an upper portion and a lower portion, a second member comprising a back wall having a mid-panel, two opposite wings articulated thereto and two opposite ears articulated to said wings respectively, a bottom member of polygonal form, articulated at its upper edge to said mid-panel, a transverse score line dividing said bottom member into two parts, opposite feet articulated to the opposite edges of the lower portion of said bottom member, a downwardly reaching foot articulated to the bottom edge of said bottom member, means for attaching the opposite ears of the main and second member together respectively, said second member being located behind said main member and adapted to reinforce the upper portion of said main member, the lower portion of said main member being brought forward to admit the bottom portion of the second member and means for securing the downwardly reaching foot of the bottom member to the lower portion of the mid-panel of the main member, the whole being foldable into collapsed condition by folding the bottom member upwardly along its transverse score line, against the main member mid-panel.

5. A collapsible container of sheet material including in combination, a main member comprising a mid-panel, two opposite wings articulated thereto and two opposite ears articulated to said wings respectively, a transverse cut dividing said mid-panel and said wings into an upper portion and a lower portion, a second member comprising a back wall having a mid-panel, two opposite wings articulated thereto and two opposite ears articulated to said wings respectively, a bottom member of polygonal form, articulated at its upper edge to said mid-panel, a transverse score line dividing said bottom member into two parts, opposite feet articulated to the opposite edges of the upper portion of said bottom member and similar opposite feet articulated to the opposite

edges of the lower portion of said bottom member, a downwardly reaching foot articulated to the bottom edge of said bottom member, means for attaching the opposite ears of the main and second members together respectively, said second member being located behind said main member and adapted to reinforce the upper portion of said main member, the lower portion of said main member being brought forward to ad-

5
10 mit the bottom portion of the second member

and means for securing the downwardly reaching foot of the bottom member to the lower portion of the mid-panel of the main member, the opposite feet of the bottom member being foldable downwardly for supporting said bottom member when the device is erected, the whole being foldable into collapsed condition by folding the bottom member upwardly along its transverse score line, against the main member mid-panel.
